UNITED STATES PATENT OFFICE.

JOSEPH C. G. LIBERT, OF PARIS, FRANCE, ASSIGNOR TO JOHN A. PRAY
WILLIAM H. PRAY, AND IVERS W. ADAMS, OF BOSTON, MASSACHUSETTS.

DESIGN FOR CARPETS.

Specification forming part of Design No. 9,372, dated July 4, 1876; application filed June 26, 1876.
[Term of Patent 3½ years.]

To all whom it may concern:

Be it known that I, JOSEPH C. G. LIBERT, of Paris, in the Department of Seine and Republic of France, have invented a new and original Design for Carpets, of which the following is a specification:

The nature of my design is fully shown in the accompanying photographic illustration.

I claim—

The design for carpets, as shown in the accompanying photographic illustration.

In testimony whereof I have signed my name to this specification in the presence of two subscribing witnesses.

JOSEPH CONSTANT GUSTAVE LIBERT,
17 Rue Poissonnière, Paris.

Witnesses:

HENRY COMTE,
MARTIN SÉRANS.
